J. G. CHAPMAN

SPINNING MACHINE

Filed Aug. 11, 1923

Fig. 1.

Inventor

John G. Chapman.

By Cuthman, August Darby
Attorney

UNITED STATES PATENT OFFICE.

JOHN G. CHAPMAN, OF TALLADEGA, ALABAMA.

SPINNING MACHINE.

Application filed August 11, 1923. Serial No. 656,950.

To all whom it may concern:

Be it known that I, JOHN G. CHAPMAN, a citizen of the United States, residing at Talladega, in the county of Talladega and 5 State of Alabama, have invented new and useful Improvements in Spinning Machines, of which the following is a specification.

This invention relates to spinning machines, and more particularly to a mechanism 10 for building a "bunch" of yarn on the bobbins when the ring rail is first started.

An object of the invention is to provide a mechanism which will cause the ring rail to start off at the bottom of its first stroke 15 very slowly and to continue the slow motion until a bunch of such length as desired has been built, whereupon the mechanism will automatically operate to increase the speed of the ring rail to complete the operation. 20 In bunch builders such as have heretofore been constructed the ring rail is held substantially stationary in order to permit the winding of a small ring of yarn at the beginning of the building operation. In other 25 devices the ring rail is given a short reciprocating movement considerably shorter than the regular movement of the rail to permit the building of the bunch.

The present construction contemplates the 30 starting of the ring rail off with its first stroke very slowly and to continue this slow traverse motion to form the bunch, if desired, for the complete traverse of the ring rail in one direction, the mechanism there- 35 after operating automatically to traverse the ring rail at its normal speed to wind the yarn.

Referring to the accompanying drawings, wherein there is shown one form of the de- 40 vice illustrating the inventive idea:

Fig. 1 is a sectional elevational view, and Fig. 2 is a detail view.

Referring to the drawings for a more detailed description, 10 indicates, conven- 45 tionally, the frame of a spinning machine, in which is mounted the drive shaft 11 having bearings in brackets 12 mounted upon the frame and adapted to receive power from any suitable source (not shown), as through 50 a worm gear 13, although other means could be employed to drive the shaft.

A ring rail traverse device, in the present instance a cam, is indicated at 14 and is adapted to reciprocate the ring rail through 55 any suitable mechanism (not shown), such as is well known in the art. It is not

thought necessary to show or describe any particular mechanism for connecting the cam to a ring rail since the invention does not relate to the same. Moreover, it will be 60 understood that the cam 14 is shown merely for the purpose of illustrating the invention, which is not limited in its application specifically to a cam for operating the traverse rail. When the term "cam" throughout 65 the specification and claims is used, it should be interpreted as covering a cam or any device having an equivalent function.

In the present instance the cam is shown as revolvably mounted upon the shaft 11 and 70 is fixed to a sleeve 15 freely mounted upon the shaft and held in position against movement longitudinally thereof by means of a collar 16. The sleeve carries a clutch member 17 cooperating with a double faced 75 clutch member 18 keyed to the shaft by means of a key 19 and slideable longitudinally of the shaft. The clutch member 17 is formed upon a gear 20 fixed to the sleeve 12 and meshing with a gear 21 upon a shaft 80 22 mounted in bearings 23. Another gear 25, also secured to the shaft 22, meshes with a gear 26 rotatable with the drive shaft 11 and held against longitudinal movement 85 thereon by means of collars 27. The gear 26 is formed with a clutch member 28 co- 90 operating with the slideable clutch member 18 and, obviously, when the latter is moved into engagement with the clutch member 28 upon the gear 26 the cam is rotated from the 90 shaft 11 through the reduction gears 25, 21 and 20. When the slideable clutch member 28 is in the position shown in Fig. 1 the cam 14 is rotated directly from the shaft and at 95 a higher rate of speed than when it is operated through the train of gearing described.

As shown in Fig. 1, the mechanism is in its normal operating position for traversing the ring rail at the usual speed for the 100 winding operation. At the starting, however, the cam 14 is rotated through the train of gearing described so that it will be operated at a slower speed for the building 105 of the bunch.

The invention contemplates the provision of automatic means for shifting the clutch member 18 from engagement with the gearing at the completion of the bunch into engagement with the clutch face 17. For this 110 purpose a bell crank lever 30 may be fulcrumed at 31, the same having a fork 32

fitting within a circumferential groove 33 in the clutch member 18. The arm 30' of the bell crank is connected at 34 to a spring 35 suitably anchored at 36 to the shaft bearing 12, the spring normally tending to raise the arm 30' of the lever into the position shown in Fig. 1. At the start of the building operation the lever is held depressed by means of an arm 40 pivotally mounted 10 at 41 upon a bracket 42 and having a shoulder 43 beneath which the arm 30' of the lever may be positioned to hold the clutch member 18 in engagement with the clutch member 28. For automatically releasing the bell crank to permit the spring 35 to shift the clutch the arm 40 is extended upwardly and has a finger 40' engaging a cam 44 fixedly mounted upon the drive shaft 11 by means of a set screw 45. The arm 40 is held in engagement with the cam 44 by means of a spring 47 anchored at 48 to an adjacent portion of the frame 10. As the drive shaft revolves the cam 44 engages the finger 40' and throws the arm to the right, as viewed in Fig. 2, permitting the spring 35 to lift the lever 30 and shift the clutch.

It will be observed that by releasing the set screw 45 the cam may be adjusted about 30 the shaft 11 in order to vary the period of rotation of the traverse cam through the reduction gearing. This adjustment will, of course, alter the length of the bunch and permit the same to be built up for one complete stroke of the rail at the slower speed, or for a portion of a stroke, as may be desired. The slow motion of the rail cannot exceed a portion of one revolution of the cam which will cause the first upward stroke of 40 the rail since thereafter the clutch will be automatically shifted to cause the traversing of the rail at the desired speed directly from the drive shaft 11. When the traverse cam is operated through the reduction gears 45 its speed will depend upon the ratio of these gears, which should be such as to rotate the cam and move the ring rail during this period at a sufficiently slow rate of speed to cause the yarn to be wound substantially 50 horizontally and to be wound upon itself.

It will be understood that numerous modifications may be made in the structure which has been illustrated and described without departing from the scope of the invention, 55 which is more definitely defined in the following claims.

I claim:

1. In a spinning machine, a ring rail traverse cam, variable speed means for driving said cam, and means for automatically varying the speed of rotation of said cam to effect the building of a bunch.

2. In a spinning machine, a ring rail traverse cam, variable speed means for driving said cam, and means for automatically

ically varying the speed of rotation of said cam to effect the building of a bunch, said last mentioned means being adjustable to permit the selection of any desired point in the rotation of the cam for changing the speed of said cam.

3. In a spinning machine, a ring rail traverse cam, means for driving said cam at one speed to permit the building of a bunch and at a higher rate of speed thereafter, means for automatically changing the speed of said cam at a predetermined point in the rotation thereof, and means selectively operable to vary the period of rotation of the cam at the slower rate of speed.

4. In a spinning machine, a driving shaft, a ring rail traverse cam driven from said shaft, means for revolving said cam from said shaft at different rates of speed without varying the speed of rotation of the shaft to effect the building of a bunch, and means for changing the speed of said cam automatically at a predetermined point in the operation thereof.

5. In a spinning machine, a driving shaft, a ring rail traverse cam driven from said shaft, means for revolving said cam from said shaft at different rates of speed without varying the speed of rotation of the shaft, and means for changing the speed of said cam automatically at a predetermined point in the operation thereof to build a bunch, said last mentioned means being adjustable to change, selectively, the point in the rotation of the cam at which its speed is varied.

6. In a spinning machine, a driving shaft, a ring rail traverse cam revolvably mounted on said shaft, means including a train of reduction gears selectively operable from said shaft and adapted to rotate said cam, selectively operable means for driving said cam at a higher rate of speed from said shaft, and automatic means for changing the drive of said cam from said first mentioned means to the latter to effect the building of a bunch.

7. In a spinning machine, a driving shaft, a ring rail traverse cam revolvably mounted upon said shaft, a train of reduction gears operatively associated with said cam to drive the same from said shaft, means adapted to drive said cam directly from said shaft or from the shaft through said train of gears, and means for automatically driving the cam from said shaft directly after it has been rotated for a predetermined period through said gears to build a bunch.

8. In a spinning machine, a driving shaft, a ring rail traverse cam revolvably mounted upon said shaft, a train of gears operatively associated with said shaft and with said cam to drive the latter at a reduced speed from said shaft to build a bunch, a clutch upon said shaft adapted to connect the shaft with

the cam either directly or through said gears, and means for automatically throwing said clutch to change the connection of the shaft with the cam after the operation 5 of said cam for a predetermined period through said gears.

9. In a spinning machine, a driving shaft, a ring rail traverse cam revolvably mounted upon said shaft, a train of gears operatively 10 associated with said shaft and with said cam to drive the latter at a reduced speed from said shaft to build a bunch; a clutch upon said shaft adapted to connect the shaft with the cam either directly or through said 15 gears, and means for automatically throwing said clutch to change the connection of the shaft with the cam after the operation of said cam for a predetermined period through said gears, said last mentioned 20 means being adjustable to vary the period of rotation of the cam through said gears.

10. In a spinning machine, a shaft, a ring rail traverse cam on said shaft, driving means, a train of gears operatively associ-

ated with said cam through which said driving means is adapted to revolve said cam, means for operating said cam at a higher rate of speed from said driving means, and means for automatically increasing the speed of the cam at a pre-determined point 25 30 in the operation thereof after a bunch has been built.

11. In a spinning machine, a shaft, a ring rail traverse cam on said shaft, driving means, a train of reduction gears through 35 which said driving means is adapted to operate the cam, means for operatively connecting said driving means with the cam independently of said gears to drive the cam at a higher rate of speed, and means for 40 automatically shifting the drive of the cam from said gears to said connecting means at a predetermined point in the operation of said cam after the bunch has been built.

In testimony whereof I have hereunto set 45 my hand.

JOHN G. CHAPMAN.
